FEELER MECHANISM FOR LOOMS.

Application filed March 30, 1926. Serial No. 98,517.

This invention relates to feeler mechanisms for looms whereby the operative condition of the loom is changed upon substantial exhaustion of the filling in the 5 shuttle.

It is now the ordinary practice to provide filling carriers with a preliminary winding of filling, or a "bunch", so called, to cooperate with a feeler to call for a change in the 10 loom operation, such, for instance, as replenishment of filling or loom stoppage, when the feeler detects a substantial exhaustion of the filling comprising the preliminary windings or bunch. Since the feeler is 15 to be controlled as to its functional operation by the amount of filling remaining in the preliminary windings or bunch, much uncertainty results as to the amount of filling remaining on the filling carrier when replenishment is effected. The amount of filling 20 remaining on the filling carrier when it is ejected from the shuttle constitutes waste and for economic reasons should be as small as possible consistent with laying a full pick 25 of filling in the shed under proper tension on the last flight of the shuttle preceding replenishment.

One of the objects of the present invention, therefore, is to provide for a minimum 30 amount of waste on filling carriers when they are ejected from the shuttle, and to this end the invention consists primarily in providing the filling carrier with two bunches, spaced apart longitudinally of the filling 35 carrier, to permit the feeler to engage the filling carrier between the bunches on a detecting beat, and to be held from functional operation to call for a change of filling until one of the bunches has been depleted. Under 40 these conditions it is apparent that one of the bunches may be formed of a predetermined amount to constitute the wastage remaining on the filling carrier when it is ejected, while the other bunch will constitute 45 a preventer bunch to prevent the feeler from calling for a change of filling until the filling in the preventer bunch has been depleted. In these respects the present application is a continuation in part of a prior 50 application by the same inventors, Serial No. 17,068, filed March 20, 1925.

In accordance with the present invention, the filling carrier, as above stated, is provided with a main or wastage bunch and a preventer bunch, separated longitudinally of 55 the filling carrier to provide a space between the bunches for engagement of the filling carrier or bobbin by a side slipping feeler when the working supply of filling between the bunches has been depleted, the 60 preventer bunch acting at such times to prevent side slipping movement of the feeler to call for a change of filling until the filling constituting the preventer bunch has been woven into the cloth, and thereupon, permitting 65 the feeler to function and call for a change of filling.

The invention and new features thereof will best be made clear from the following description and the accompanying drawings 70 of one good form thereof.

In the drawings:

Fig. 1 is a perspective view at the feeler side of a loom containing the present invention;

Fig. 2 is a top plan view showing the relation of parts when the feeler engages a working supply of filling between the bunches on the filling carrier;

Fig. 3 is a similar view showing the relation of parts when the filling between the bunches has been depleted and the preventer bunch is acting to prevent side slipping movement of the feeler;

Fig. 4 is a view similar to that of Fig. 3 85 showing the filling on the preventer bunch as having been partially exhausted but still acting to prevent side slipping movement of the feeler; and

Fig. 5 is a view similar to that of Fig. 4 90 showing the preventer bunch as having been exhausted and the feeler freed to its side slipping movement.

In the form of the invention herein shown the feeler is associated with a train of mechanism for calling for replenishment of filling when the filling on the preventer bunch has been depleted, but the replenishing mechanism is not herein shown because the details thereof form no part of the present 95 invention and such mechanism may be of any usual or preferred type now well known.

In accordance with the present invention, the feeler may be of the side swipe type but of any usual character, and as herein shown the feeler is of the construction more fully illustrated and described in the application of Brown & Repass, Serial No. 45,349, filed July 22, 1925, but in the present application no claim is made herein for the structural features of the feeler, since such claims already form the subject-matter of the pending application above mentioned.

The loom frame 1 may be of any desired construction, and rising from the usual transverse shaft is the arm 2 to which is pivoted at 3 the actuator 4 the rear end portion of which is provided with a housing 5 having an opening 6 into which may be projected an operating member herein constituted as a part 7 connected to the cam follower. Pivotaly mounted on lugs 8 extending from the housing 5 is a lever 9 to which is connected the actuator 10, the other end portion of which extends into the opening 11 in the feeler stand. These parts are herein shown as of the same type and construction as those more fully illustrated and described in the copending application above mentioned but it is to be understood that so far as the present invention is concerned, such transmitting mechanism to call for a change of filling under functional operation of the feeler may be of any suitable character.

Extending from the loom frame is the shipper stand 12 to which is secured by a bolt 13 a bracket 14 supporting the feeler stand 15. The feeler 16 has the toothed or roughened end portion 17 and is mounted on the feeler stand 15 for movement towards and from the front of the loom and also in a direction longitudinally of the shuttle. The feeler 16 has the laterally extending portion 18, the toe 19 of which is adapted to engage a stop or lug 20 carried by the feeler stand. Connected to the lateral extension 18 is a spring 21 which may be secured at one end to the lateral extension by a bend, as at 22, and the other end of the spring may be secured to a projection 23 at the rear of the feeler stand, the construction being such that the normal tendency of the spring 21 is to move the feeler rearwardly to its full feeling position and yet permit side swipe movement of the feeler.

It will not be necessary herein to more fully describe the construction and operation of the feeler 16 since this mechanism is shown as substantially the same as that in the co-pending application, Serial No. 45,349, and the structural details thereof form no part of the present invention, because so far as the present invention is concerned any feeler of the side swipe type may be used.

The lay 24 is provided with the usual

shuttle box 25 for the reception of the shuttle 26 in which the filling carrier 27 is mounted, and the front wall of the shuttle box is provided with an opening 28 which registers with a similar opening 29 in the front wall of the shuttle when the latter is properly boxed, as indicated in Fig. 1, the construction being such that on a detecting beat the feeler may enter the shuttle and feel for the filling.

In accordance with the present invention, the filling carrier 27 is provided with the usual head 30 by which the filling carrier may be detachably held in the shuttle by the usual holding jaws 31 carried by the shuttle. The filling carrier 27 has a main or wastage bunch of filling 32 which in the present instance is shown as wound upon the filling carrier 27 adjacent the head thereof, and it also has wound thereon a preventer bunch 33 separated from the main or wastage bunch 32 by a space 34, Fig. 2, sufficient in extent to permit the end of the side swipe feeler to engage the filling carrier between the bunches when the working supply of filling between the bunches has been withdrawn.

The feeler, in the present instance of the invention, is shown as of the type wherein it is given its side swipe movement by the frontward pressure of a surface within the shuttle, such, for instance, as the surface of the filling carrier 27, and when the filling between the two bunches has been depleted and the feeler engages the filling carrier between the bunches, the normal tendency of the frontward pressure of the filling carrier is to cause side swipe movement of the feeler. Owing, however, to the preventer bunch 33, an obstruction is presented to such side swipe movement, and such obstruction continues to be presented to the feeler on detecting beats until such obstruction is removed by depletion of the filling in the preventer bunch. In Fig. 4 the filling in the preventer bunch is shown as partially depleted, but still the obstruction to the side swipe movement is presented to the feeler, until when the filling in the preventer bunch is entirely exhausted, as indicated in Fig. 5, the feeler is freed to its side swipe movement to initiate filling replenishment.

Since the feeler partakes of its side swipe movement when the filling in the preventer bunch has been depleted, it is obvious that the amount of filling in the main or wastage bunch may be of predetermined amount and is preferably of an amount sufficient to permit a full length of filling to be laid in the shuttle under proper tension after the filling in the preventer bunch has become exhausted. Thus the amount of wastage remaining on the filling carrier when it is ejected from the shuttle can be predetermined and mini-

mized to an amount sufficient only to permit a full pick of filling to be laid in the shed under proper tension on depletion of the preventer bunch.

5 Applicants believe themselves to be the first in the art to provide a feeler mechanism wherein the filling carrier has a main or wastage bunch and a preventer bunch spaced from the main or wastage bunch to permit 10 the feeler to engage the filling carrier between the bunches when the working supply of filling between the bunches has been exhausted, and applicants further believe themselves to be the first in the art to provide, in 15 connection with such filling carrier having a main or wastage bunch and a preventer bunch spaced therefrom, a side slipping feeler held from side slipping movement by the obstruction offered by the preventer bunch 20 until the filling thereof has been depleted, thereupon freeing the feeler to its side slipping movement. It is to be understood, of course, that the filling constituting the main or wastage bunch and the preventer bunch is 25 continuous, so that when the filling of the preventer bunch has been depleted, the filling in the main or wastage bunch will be laid in the shed.

While the present invention has been described in connection with a filling carrier or bobbin having two bunches wound thereon with a space between, which is a simple and preferred form, yet it is to be understood that the filling carrier of the present 35 invention may have any desired number of bunches as more fully disclosed in the application Serial No. 17,068, before mentioned, and of which this is a continuation in part.

40 What is claimed is:

1. In a feeler mechanism for looms, the combination of a shuttle having a filling carrier provided with a main bunch of windings and a preventer bunch of windings spaced from the main bunch, and a side slipping feeler mounted to engage the filling carrier in the space between the bunches when the main windings are withdrawn and be held from side slipping movement on a 45 detecting beat by the preventer bunch until its depletion and thereupon be freed to its side slipping movement.

2. In a feeler mechanism for looms, the combination of a shuttle having a filling carrier with service filling wound thereon and provided with a main bunch or predetermined amount of filling constituting waste when the filling carrier is ejected on replenishment of filling and a preventer bunch 50 spaced from the main bunch, a side slipping feeler mounted to engage the filling carrier in the space between the bunches and held from side slipping on a detecting beat by the obstruction formed by the preventer bunch until such obstruction is removed by

depletion of the preventer bunch.

3. In a feeler mechanism for looms, the combination of a shuttle having a filling carrier with filling wound thereon and provided with a main bunch adjacent the head of 70 the filling carrier and a preventer bunch spaced from the main bunch, a feeler having teeth which engage the filling carrier between the two bunches and is prevented from side slipping along the filling carrier on a 75 detecting beat by side contact with the preventer bunch until the preventer bunch is depleted, and means controlled by the feeler for effecting replenishment of filling.

4. In a feeler mechanism for looms, the combination of a shuttle having a filling carrier with filling wound thereon and provided with a main bunch constituting waste and a preventer bunch spaced from the main bunch, a side slipping feeler mounted to engage the filling between the two bunches when a working supply occupies said space and to engage the filling carrier between the bunches when the filling in said space is depleted, and means controlled by the feeler 80 to effect replenishment of filling when the preventer bunch is depleted and the feeler is freed to its side slipping movement.

5. In a feeler mechanism for looms, the combination of a shuttle having a filling carrier with filling wound thereon and provided with two bunches of filling in spaced relation, a feeler mounted at the front of the loom to enter the shuttle on a detecting beat to engage the filling carrier between the 95 bunches when the filling between them is depleted, and means controlled by the feeler to effect replenishment of filling.

6. In a feeler mechanism for looms, the combination of a shuttle having a filling carrier with filling wound thereon and provided with two bunches of filling, a feeler extending rearwardly from the front of the loom to enter the shuttle and engage the filling carrier between the two bunches when the 100 filling is nearly exhausted and mounted for side slipping movement along the filling carrier by the forward pressure of the filling carrier on a detecting beat but held from such movement by one of said bunches until 105 exhaustion thereof, and means controlled by the feeler to effect a change in the loom operation.

7. A filling carrier or bobbin provided with filling and having two bunches of filling wound thereon which are exposed when the main filling winds are withdrawn, said bunches of filling being separated by a space to permit the end of a feeler to engage the filling carrier or bobbin between the bunches.

8. A filling carrier or bobbin provided with filling and having a main bunch of filling wound thereon adjacent the head of the filling carrier or bobbin and a preventer bunch separated longitudinally of the filling 120

carrier or bobbin to provide a space between them for contact of the filling carrier or bobbin by the end of a feeler when the main filling winds have been withdrawn.

5. 9. A filling carrier or bobbin provided with filling and having two bunches of filling wound thereon and separated by a space to permit the end of a feeler to engage the

filling carrier or bobbin between the bunches when the main filling windings have been ¹⁰ withdrawn, the filling being continuous between the bunches.

In testimony whereof, we have signed our names to this specification.

LARKIN H. BROWN.
GEORGE E. REPASS.
